UNITED STATES PATENT OFFICE

109,746

DESIGN FOR A HAT

Abraham Van Laven, Brooklyn, N. Y.

Application January 15, 1938, Serial No. 74,331

Term of patent 7 years

To all whom it may concern:

Be it known that I, Abraham Van Laven, a citizen of the United States, residing at Brooklyn, in the county of Kings and State of New York, have invented a new, original, and ornamental Design for a Hat, of which the following is a specification, reference being had to the accompanying drawing, forming a part thereof.

Fig. 1 is a plan view of a hat showing my design viewed from the back, and

Fig. 2 is a rear perspective of the hat shown in Fig. 1.

Fig. 3 is a front view thereof.

I claim:

The ornamental design for a hat as shown.

ABRAHAM VAN LAVEN.
